UNITED STATES PATENT OFFICE.

GEORGE F. WINTER, OF LOS ANGELES, CALIFORNIA.

SAFETY-GATE.

1,347,198.

Specification of Letters Patent.

Patented July 20, 1920.

Application filed October 28, 1919. Serial No. 334,062.

To all whom it may concern:

Be it known that I, GEORGE F. WINTER, a citizen of the United States, residing at Los Angeles, in the county of Los Angeles and State of California, have invented a new and useful Safety-Gate, of which the following is a specification.

The object of this invention is to increase the safety to passengers entering and leaving 10 elevators or lifts or going through passways controlled by edgewise moving closures.

A serious source of danger to such passengers arises from the forceful closing of heavy elevator doors by mechanisms such as 15 pneumatic or hydraulic door closing apparatus now coming into general use, and an object of this invention is to avoid all danger that a leg or arm of any passenger entering or leaving an elevator will be caught by 20 the closing door.

The invention pertains to the construction of elevator doors and the provision and arrangement of a buffer or buffers therefor. Other objects of the invention are simplicity, 25 strength and cheapness of construction.

Other objects, advantages and features of the invention may appear from the accompanying drawings, the subjoined detail description and the appended claims.

30 The accompanying drawings illustrate the invention.

Figure 1 is an elevation of an elevator double door constructed in accordance with this invention and shown partly open. Pneumatic operating apparatus is also indicated diagrammatically.

Fig. 2 is a fragmental elevation of a lower part of the door edge and buffer.

Fig. 3 is an elevation in section on line w^3 , 40 Fig. 1.

Fig. 4 is a front elevation of a double door of somewhat different construction.

Fig. 5 is a front elevation of a double door of the character shown in Fig. 1 fully closed.

Fig. 6 is a fragmental elevational detail of closure frames and buffers at the lower middle part of Fig. 5; the doors being partly open.

50 The frames of the edgewise moving closure means shown to close a passway or doorway Fig. 1, are constructed of U-shaped metal bars comprising the rear upright 1 and the horizontal bottom and top limbs 2, 3, of one edgewise moving door body or clo-

sure a , and the rear upright 1" and the horizontal bottom and top limbs 2", 3", of the second door body b .

Within each of said frames is a grid, which may be made of any suitable form and is shown terminating in the forward marginal member 4, which is parallel to the rear upright member 1. The horizontal members 2 and 3 project forwardly beyond the upright forward marginal member 4 and are 65 provided with resilient buffer means 5 adapted to contact with opposed buffer means so that the closing of the door will be accomplished without jar. The grids which terminate in the marginal members 4 70 may be made of any suitable construction and are shown as opposing uprights 6 and horizontal bars 7.

As seen in Fig. 4, when the two edgewise moving closures are closed there is considerable space between the front marginal bars 4 of the two door bodies; and when said door bodies are brought together, the space between the marginal bars 4 is such as to accommodate a limb as the leg, foot, arm or 80 hand of a passenger or other person, so that no crushing effect will result from closing the door while the limb of a person entering, leaving or standing in the elevator, not shown, is in the passageway. This space 85 may accommodate such portions of the body without allowing ingress or egress of the entire body; and in order to give more complete closing effect without injury to limb of the passenger, yielding means indicated 90 as a coiled spring buffer 8 is provided and is attached to the projecting portions 9, 10 of the lower and upper limbs of the door frame.

For convenience the ends of the portions 9, 10 may be provided with crooks 11 to 95 which the resilient buffers 8 are connected.

In Fig. 5 the resilient buffer is shown connected to projection 11 at the top of the edgewise moving closure c and when the two closures c , d shown in Fig. 5 are closed as 100 shown in said Fig. 5, the resilient buffer 8 stands at the middle of the space between the marginal upright bars 4 and will be deflected by pressure upon the interposed limb; such space 12 between the upright bars 4 105 being of such width as to accommodate said limb and said width being determined by the length of members 9 and buffers 5.

The edgewise moving closures are mounted in the usual way upon head rail 13 by 110

means of antifriction hangers 14 and said doors are operated in practical use by any suitable means as the pneumatic apparatus 15 well known in the art and connected to the doors by any well known suitable means not detailed.

10 The bottoms of the edgewise moving closures may be accommodated within a channel 16 in the floor 17 of the elevator or other structure to which the invention is applied.

15 In practice the edgewise moving closure will be operated to and fro in the usual doorway or passway 18, and in case the limb of any person should be in the passway 18, at the closing of the same, the resilient buffer 8 will strike the limb that is in the way thus giving warning and then will yield without crushing the limb.

I claim:

20 1. The combination with a passway of edgewise moving closure means for said way and means for stopping said closure means at such point as to accommodate a limb of a person in case such limb is in the way at the shutting of the closure means.

25 2. The combination with a pass-way of closure means comprising a rigid closure frame and buffer means extending beyond the edge of the rigid closure frame and means against which said buffer means are stopped at the end of the closing operation so as to accommodate a limb of a person without crushing the same in case such limb is in the way when the closure means are closed.

30 3. In combination with an opposing upright, an elevator door comprising a rigid frame having a rigid edge member to cooperate with the opposing upright, and buffer means projecting beyond said edge member; stop means to stop said door at such a point as to accommodate the limb of a person in the space between said edge and the opposing upright for the purpose of avoiding injury to such limb.

35 4. An edgewise moving elevator door comprising a rigid section constituting the main portion of the door and a yielding edge member carried by the door to contact with a limb of a person at said door without crushing said limb when the door is closed.

50 5. An edgewise moving door comprising a rigid frame provided with projecting arms at one edge thereof and a spiral spring connected to said arms and forming a yielding edge to said door.

55 6. An edgewise moving door comprising a rigid frame provided with projecting arms at one edge thereof and a yielding member

connected to said arms and forming a yielding edge to said door.

60 7. In combination with a doorway and pneumatic door operating means; an edge-wise moving door operated by said pneumatic means, and provided at its forward edge with yielding means to contact with, and to accommodate without crushing, the limb of a person in case the same were to be caught in the path of said door in the operation of closing the door.

65 8. The combination with a passway of edgewise moving closures for said doorway, each of said closures being provided at its edge with rigid edge members and with upper and lower arms and yielding buffers 75 on said arms, said buffers being adapted to contact with each other upon closing the passway, to leave an open space between said doors to accommodate the limb of a person at the doorway.

70 9. The combination with an elevator doorway of two edgewise sliding closures for said doorway, said closures being provided at their abutting edges with projections at top and bottom beyond the rigid edges of 85 said doors, and a yielding edge member connected to the upper and lower projections of one of the doors to form a yielding upright intermediate the rigid edge members of said doors.

75 10. An elevator door provided with upper and lower projections and a coiled spring fastened to and extending between said projections at a distance from the rigid edge of the door.

80 11. An elevator doorway provided with a grooved sill and a stop; an elevator door to close said doorway and having its lower end running in the groove of said sill and provided with a projection in said groove 100 to engage the stop so as to leave a limb accommodating opening at the edge of the door when the door is closed.

85 12. An elevator doorway provided with a grooved sill, an elevator door to close said doorway and having at its lower end a projection running in the groove of said sill, and a coiled spring connected to said projection and extending upward therefrom and connected to said door to form a yielding 110 edge therefor.

In testimony whereof, I have hereunto set my hand at Los Angeles, California, this 23d day of October, 1919.

GEORGE F. WINTER.

Witness:

JAMES R. TOWNSEND.
